[57] CLAIM

The ornamental design for an automobile carriage rack,
as shown and described.

DESCRIPTION

FIG. 1 is a right side elevational view of an automobile carriage rack showing my new design, the broken lines being shown for illustration purposes only.

FIG. 2 is a perspective view thereof.

FIG. 3 is a back elevational view thereof.

FIG. 4 is a left side elevational view thereof.

FIG. 5 is a front elevational view thereof taken along line 5—5 of FIG. 4.

FIG. 6 is a bottom plan view thereof taken along line 6—6 of FIG. 5.

FIG. 7 is a top plan view thereof taken along line 7—7 of FIG. 5.
